Inventor:

Carl Neuhaus.

UNITED STATES PATENT OFFICE

KARL NEUHAUS, OF GLEIWITZ, GERMANY, ASSIGNOR TO ADOLF KRAH, OF GLEIWITZ, GERMANY

INGOT-HEATING FURNACE

Application filed May 9, 1928, Serial No. 276,312, and in Germany May 20, 1927.

On rolling or other working metals, the ingots are generally heated in an elongated furnace through which they are pushed from one end to the other. The heat is supplied to the principal heating zone which is situated at the delivery end of the furnace. The extension of the heating zone is limited, and the rate at which the rolling takes place with modern machinery, (usually one ingot a minute) does not allow the ingots to stay any length of time in the principal heating zone. The intensity of the heat supplied to this zone is therefore considerable; but although the ingots may, on leaving the furnace, be in a state of white heat, it is found that they rapidly cool down in the rolling mill to a dull red. This is evidently due to the shortness of the time during which the ingots are exposed to the intense heat which only penetrates the outer portion of the ingot, the core being still comparatively cool.

The object of the present invention is to remedy this defect, and the invention consists in the provision of a furnace having, beyond the principal heating zone, a heat-equalizing zone wherein the ingots are retained after leaving said principal zone so as to allow the heat to penetrate to the core, the ingots being meanwhile exposed in said heat-equalizing zone to a lower temperature.

Fig. 1 of the accompanying drawings represents a vertical longitudinal section of a furnace according to the invention, and

Fig. 2, a horizontal section of the same. The elongated furnace structure has a hearth which extends from end to end. The principal heating zone *a* occupies an intermediate portion of the structure and receives the heat from combustion chambers *f*¹ and *f*² arranged at opposite sides of the hearth.

At one side of the principal heating zone there is a pre-heating zone *i* which occupies one end portion of the structure. At the other side there is a heat-equalizing zone *h* which occupies the other end portion of the structure. The ingots *b* are introduced into the preheating zone at the end of the structure and pushed in known manner along guide rails *g*, *g*¹ through the different zones in succession. There is a lateral outlet *t* in

the heat-equalizing zone through which the ingots are withdrawn from the furnace for rolling or other treatment. The hot gases from the principal heating zone are diverted over the hearth in both directions. Those gases which pass through the preheating zone above the hearth and the ingots are discharged through flues *k*¹ which are fitted with dampers *s*¹. The gases going in the opposite direction are led to the under side of the hearth, partly direct through a flue *n* in the hearth near the combustion chambers, thus without loss of heat, and partly through a flue *l* at the extreme end of the heat equalizing zone after having passed over and transmitted heat to the latter. These gases pass under the entire hearth and row of ingots to a discharge flue *k*² which is fitted with a damper *s*². By adjusting the dampers *s*¹ and *s*² and by suitably dimensioning the flues *l* and *n* the flow of gas can be regulated so that more or less will be led through the equalizing zone according to requirements.

By the provision of an equalizing zone as described, the ingots will have time to get uniformly heated throughout, and they will therefore be better able to retain their heat during the rolling, even if the uniform temperature should be less than the surface temperature at which the ingots are removed from furnaces of known type.

The actual construction of the furnace structure may be varied within the scope of the invention which is applicable to recuperative as well as regenerative furnaces. Instead of arranging the combustion chambers *f*¹ and *f*² at the sides of the hearth, they may be arranged above or below it, the paths pursued by the gases being varied accordingly.

I claim:

An ingot heating furnace comprising an elongated furnace structure having at one end a preheating zone, at the other end a heat-equalizing zone, and between the two a principal heating zone, a hearth extending through the three zones, means for guiding the ingots along said hearth towards the heat-equalizing zone, means for supplying heat to the principal heating zone, means for leading part of the gases from the principal

heating zone over the hearth through the pre-heating zone, means for leading another part of the gases to the under-side of the hearth, partly direct through the latter and partly at the end of the heat equalizing zone, and means for discharging the gases at the end of the preheating zone.
